TELEVISION SYSTEM

Theodore A. Smith, Ridgewood, N. J., assignor to
 Radio Corporation of America, a corporation
 of Delaware

Application June 11, 1929, Serial No. 369,973

4 Claims. (Cl. 178—6)

The present invention relates to television systems, and, more particularly, to television systems in which the flicker occurring when television pictures are received is reduced to a minimum extent without increasing the number of pictures received per second.

It is well known in the art to which this invention relates that the intensity of flicker occurring when television pictures are projected upon a screen so that they may be viewed by an observer or an audience is a function of the intensity with which the screen is illuminated, a function of the speed at which the screen is illuminated, and a function of the method and/or order of illuminating the screen.

With these difficulties in mind, it is one of the primary objects of my invention to provide a system wherein the objectionable flicker may be materially reduced without increasing the number of complete pictures received per second.

Still another object of my invention is to provide a method and means by which the same picture in its identical position may be projected upon the screen two or more times for the purpose of increasing the visual representation of each of the individual points from which each individual picture is composed.

Still another object of my invention is to provide a method and means whereby the same identical picture elements may be projected upon the same screen at a plurality of time separated intervals, and in the same identical position at which they were first viewed.

Other objects of my invention are to provide a method and means for projecting the same image corresponding in intensity to the intensity of light and shadow on the subject originally transmitted, whether it be a moving subject, a picture subject, a motion picture film moving at a predetermined and chosen speed, or any other type of image, which is relatively simple in its construction and arrangement of parts, a system which is readily adapted to use in connection with the now existing types of television receivers without any substantial modification thereof, a system which is efficient in its use, conveniently installed, and readily operated.

Other and ancillary objects of my invention will become apparent and at once suggest themselves to those skilled in the art to which the invention relates by reading the following specification and claims in connection with the accompanying drawing, wherein:

Fig. 1 thereof illustrates in a schematic manner one form which my invention may assume

for projecting all of the picture elements twice upon the same screen at time separated intervals; and,

Fig. 2 illustrates a modification of the arrangement disclosed by Fig. 1 wherein high frequency impulses may be projected at one period of time and low frequency impulses projected at a different period of time in accordance with the above named objects.

To refer now more particularly to the drawing forming a part of my disclosure, the system consists briefly in using a number of glow discharge lamps which are each operated from the same received signal, but are so connected with properly and appropriately designed delay circuits that the same electrical impulse applied to the common input will cause successive light variations in the lamps. The lamps may be so properly spaced about the rotating or oscillating scanning element that the delayed light falls on a corresponding part of the picture, or, in other words, each lamp is arranged to produce one complete picture for each rotation of the analyzing disk, but the pictures thus produced are so superposed that, to the eye viewing the television screen, but one single picture is apparent.

It will thus be seen that such an arrangement will reduce the flicker to a substantial extent because the picture will be illuminated in a number of places at once. This illumination will tend to multiply the frequency of the flicker by the number of lamps used, and, for example, where two lamps are used, the flicker frequency will be double the flicker frequency for a single lamp, and when five lamps are used, for example, the flicker frequency will be five times the flicker frequency for a single lamp. It is a well known fact that a higher frequency flicker is not as perceptible to the eye as a lower flicker frequency.

Now referring more particularly to Fig. 1 of the drawing, I have illustrated, in a conventional manner, a glow lamp 1, which is connected directly to an amplifying system 3 connected in turn to a television receiver supplied with energy in accordance with the intensity of light and shadow over radio, wire, or wired radio systems. In accordance with the energy derived from the received signals, the lamp 1 is arranged to produce a glow of an intensity proportional to the elemental intensities of the received picture, assuming the same to be such that for high light effects on a picture maximum current energy is transmitted, and for low light effects or dark points on a picture minimum current is transmitted.

Still another glow lamp 5 is arranged at a point removed substantially 180° from the glow lamp 1, and is likewise connected with the amplifying system 3 through a delay circuit generally designated as 7 so that the corresponding impulses producing a glow in the lamp 5 will be delayed as regards the time when they reach the lamp 5 over the period of time when they were impressed upon the lamp 1. Suppose, for example, that the number of complete television pictures received per second were n , and it is desired to use two lamps scanning the picture one-half a picture apart as shown by Fig. 1, then the delay circuit 7 must cause a lag of

15

$$\frac{1}{2n}$$

seconds for all impulses which pass through it.

For the purpose of projecting the image of the glow lamp upon the television screen 9, it is assumed that a lens or aperture disk 11 provided with lenses or apertures 13 positioned in a spiral about the periphery of the disk, in accordance with the teachings of Nipkow, is used for projecting the light from the lamp upon the screen. It is apparent that by the use of lenses 15 and 17 any light produced in either of the glow lamps 1 or 5 will be projected through the lenses 15 and 17 respectively to the screen 9, and, as shown, the separate light impulses may focus at points 19 and 21, for example. The lens 17 is so compounded as to be similar to lens 15, except that it produces no reversal of light direction passing through it as does 15. Spots 19 and 21 will, therefore, move similarly as shown by the arrows. As shown, the impulse or light spot focused at the point 19 will be approximately one-half picture ahead of the light spot focused at the point 21 on the screen 9, but the spot 21 will project the same intensity of light which had been previously projected as a spot 19 at a time one-half picture period removed from the time when the light spot is focused at the point 21.

The disk member 11 may be properly driven and rotated, for example, in the direction shown by the arrow by any appropriate and desired type of prime mover which may, in turn, be synchronized by any known and desired type of synchronizing system, for example, by synchronizing impulses transmitted simultaneously with the television signal, or by the utilization of synchronizing impulses derived through the existing power mains such as, for example, 60 cycle A. C. mains.

Now referring to Fig. 2 of the drawing, and in accordance with the principles disclosed by the schematic and conventional embodiment of Fig. 1 of the drawing, it will at once be recognized in the use of a delay circuit of the type shown conventionally at 7 that it may be advisable to pass only the lower frequencies therethrough and thus apply these lower frequencies to the lamp 5. It is generally recognized in the art to which the invention relates that the lower frequencies corresponding to slowly moving objects and objects comparable with the picture size will cause flicker more than the higher frequencies. Thus, an arrangement in which all of the received television signals are produced in the lamp 1 and only the signals of lower frequency in lamp 5 has been provided. However, such a system may cause certain portions of the picture to be brighter than others, and, to avoid repetition of the picture impulses, a high pass filter 25 may be inserted in the line connecting the glow lamp 1 with the television amplifier 3 so as to allow

the lamp 1 to reproduce the high frequency components of the picture, and the lamp 5 to produce through the low pass filter 23 and the delay circuit 7, the lower frequency components. In a similar manner, one lamp might produce a certain band of the necessary television frequencies, and the other lamp produce the remainder of the television signal band.

While I have disclosed my present invention as applied to a disk on which there is arranged a Nipkow spiral, which may be either provided with lenses or apertures, it is also readily recognized that the invention is in nowise limited to such a construction but I may substitute for the lens or aperture disk 11 a drum disk provided with lenses or apertures arranged on a helical path, or I may substitute a mirror disk or a vibratory member, which is vibrated in two planes at right angles to each other, so as to cause the light beam projected thereon to trace the image in an appropriate manner, or a series of different light producing elements successively and cyclically actuated in any appropriate manner by received signals, or I may utilize any other known and desired type of scanning or analyzing system without departing from the spirit and scope of my invention, since the invention is not per se directed to any type of scanning element only in so far as one type of scanning element cooperates with the illumination system hereinabove disclosed.

Having now described my invention, I believe myself to be entitled to make any and all modifications thereof such as fall fairly within the spirit and scope as set forth by the hereinafter appended claims, wherein, I claim and desire to secure by Letters Patent:

1. In a television system, a picture display screen, a plurality of light producing sources, an apertured scanning element for projecting independently the light from said sources through diametrically opposite apertures thereof upon said screen, and means for controlling the time of operation of each of said sources so as to illuminate the screen from each source in a sequential and time-delayed manner, whereby the same intensity of light is projected upon said screen a plurality of times at time-separated intervals for each elemental picture area, and an optical system positioned intermediate one of the light sources and the screen to cause the scanning path of the resulting light spot to correspond in direction to that of the other scanning path.

2. In a television receiving system, a scanning element having a series of apertures arranged about the periphery thereof, a plurality of light sources arranged to produce light of an intensity corresponding to the intensity of light and shadow on individual elements of a picture surface, a screen, a means provided by said scanning element for independently projecting the intensity of each of said light sources from diametrically opposite apertures upon the said screen at similar and corresponding points, means for delaying the action of each of said light sources with respect to the other whereby corresponding picture intensities are produced in a sequential and time-delayed manner and an optical system positioned intermediate one of the light sources and the screen to cause the scanning path of the resulting light spot to correspond in direction to that of the other scanning path.

3. In a television receiving system, a rotary scanning element, a plurality of light sources ar-

5 ranged to produce light of an intensity corresponding to the intensity of light and shadow on individual elements of a picture surface, a screen, means provided by said scanning element for independently projecting from diametrically opposite scanning areas thereof the intensity of each of said light sources upon the said screen at similar and corresponding points thereon, means for producing a relative time delay in the 10 periods of like illumination of each of said light sources with respect to the other, whereby corresponding picture intensities are produced in a sequential manner and projected upon said screen a plurality of times and an optical system positioned intermediate one of the light sources and 15 the screen to cause the scanning path of the re-

sulting light spot to correspond in direction to that of the other scanning path.

4. In a television system, a screen, a plurality of light sources, means for projecting light from said sources upon said screen, means for producing a portion of the frequencies contained in the electrical transmission of the television picture from one of said light sources, means for reproducing another portion of the frequencies contained in the electrical transmission of the television picture from the other of said light sources, and means for delaying the action of one of said light sources with respect to the other so as to reproduce said different frequencies at time separated intervals. 15

THEODORE A. SMITH.
